CLAIM

The ornamental design for an elevated exercise platform, as shown and described.

DESCRIPTION

FIG. 1 is a perspective view of an elevated exercise platform showing the design;

FIG. 2 is a front elevational view of the elevated exercise platform of FIG. 1;

FIG. 3 is a rear elevational view of the elevated exercise platform of FIG. 1;

FIG. 4 is a left side elevational view of the elevated exercise platform of FIG. 1, the right side elevational view is a mirror image thereof;

FIG. 5 is a top plan view of the elevated exercise platform of FIG. 1; and,

FIG. 6 is a bottom plan view of the elevated exercise platform of FIG. 1.

The broken line showing of portions of the elevated exercise platform depicts environment and forms no part of the claim.

1 Claim, 5 Drawing Sheets
